JAMES MACCONAGHY, OF BOULOGNE-SUR-MER, FRANCE; (MISSES) ELIZABETH MARY MACCONAGHY AND JANE MACCONAGHY, HEIRESSES OF SAID JAMES MACCONAGHY, DECEASED.

EXPLOSION-MOTOR.

1,083,111.

Specification of Letters Patent.

Patented Dec. 30, 1913.

Application filed September 16, 1910. Serial No. 582,308.

To all whom it may concern:

Be it known that I, JAMES MACCONAGHY, of 44er Rue Victor Hugo, Boulogne-sur-Mer, Pas-de-Calais, Republic of France, have invented an Explosion-Motor, of which the following is a full, clear, and exact description.

The present invention has for its object an explosion motor of the multiple cylinder type, capable of developing a great horse power under a small volume and applicable, by this fact, either to motor vehicles, or to apparatus for aerial locomotion. This form of motor comprises one or more groups of two superposed cylinders; the two cylinders of each group communicate with one another by a large conduit-pipe, arranged at the end opposite to that where the ignition is produced and the liquid fuel and the air are also admitted in the cylinders by the end opposite to that where the ignition is effected. The pistons moving in the cylinders are movable on their rods, so as to permit, concurrently with a valve with which each piston, is provided, the admission of the explosive mixture in front of the latter. The rods of each of the pistons control directly the air inlet valve which is placed in a housing; the liquid fuel is admitted directly by these two valves or by one of them only. A rotary valve placed at the end of each of the cylinders and controlled by a cam, allows the escape of the exhaust gases; this valve can also play the part of a make-and-break mechanism. The piston rods are controlled by a slide of special construction and these rods are hollow on a part of their length and are provided with holes permitting the escape of the gases, on the return of the piston, so as to insure the opening of the air inlet valve when the piston again moves forward. Finally, a pressure lubricating device insures a suitable lubrication of the inner parts of the motor.

The invention is illustrated, by way of example, in the accompanying drawings, in which:

Figure 1 shows, partly in elevation and partly in vertical section a motor provided with four cylinders; Fig. 2 is a corresponding plan view; Fig. 3 is a cross vertical section, made according to line A—A of Fig. 1, showing the conduit-pipe putting the two cylinders into communication with one an-

other; Fig. 4 is another vertical section, 55 made according to line B—B of Fig. 1, showing the rotary valves; Figs. 5 and 6 are two longitudinal sections of the motor showing the pistons at two points of their stroke; Figs. 7 to 14 show diagrammatically the operation of two of the pistons; Fig. 15 shows a modification of the motor.

As illustrated in Figs. 1 and 2 of the drawings, the motor comprises four cylinders a a^1 a^2 and a^3 arranged in two groups 65 placed opposite to one another. The cylinders of each group are superposed and are secured, by cramps a^4 , to the frame a^5 of the motor. The superposed cylinders a and a^1 , on the one hand, and a^2 a^3 , on the 70 other hand, communicate between them by a large conduit-pipe b placed at the end opposite to that where the ignition of the explosive mixture is to be effected. Inside the cylinders a a^1 a^2 and a^3 can move pistons c c^1 c^2 75 and c^3 moved along by rods d d^1 d^2 and d^3 secured on a slide e in which engages the cranked part of the motor shaft e^1 . As shown in the drawings, the slide e is inclined, so as to avoid the dead center, always presenting an oblique surface to the shaft e^1 . The pistons c c^1 c^2 and c^3 are not secured on the rods d d^1 d^2 and d^3 ; said pistons are movable relatively to these rods to which they are connected in the following manner:—At the end of each of the rods d is secured a metal disk f which engages within the body of the piston and upon which the latter can take a bearing. The diameter of the disk f is smaller than that of the inner 80 part of the piston c , so as to permit the explosive mixture to pass in front of the piston, as will be seen hereafter. The displacement of the piston, relatively to its actuating rod, is limited by one or more abutments f^1 85 secured inside the said piston (Figs. 1, 5 and 6).

Each of the pistons c c^1 c^2 c^3 is provided with a central opening g which may be closed inside the piston by the end of the 100 actuating rod d d^1 d^2 or d^3 and outside the said piston by a valve h the rod h^1 of which, passing through the opening g , is engaged in a hollow part formed to that effect in each of the rods d ... d^3 . The displacement 105 of each of the valves h is limited by an abutment h^2 suitably secured on the corresponding rod d .

The liquid fuel and the air are admitted in the cylinders a a^1 a^2 and a^3 by means of valves i arranged behind the conduit-pipe b putting each group of cylinders into communication with one another and, consequently, at the part opposite to that where the ignition is effected. One of the piston rods passes through each of the valves i and each valve is mounted somewhat frictionally on this rod, so as to be moved along by the latter. Each of the valves i is located in a housing j and said valves can close an annular opening k provided in the head of the cylinder and formed around the piston rod. For each group of cylinders, the two valves i always admit air. In the example illustrated in the drawings only one of the valves admits the combustible liquid. The latter, supplied by a pipe l perforated with small orifices, is simply sucked in when the valve i opens. This arrangement permits to do away with the carburetor and the accessories of the latter. In certain cases, the combustible liquid can be admitted by the two valves i of each group of cylinders.

At the front part of each cylinder, that is to say at the part opposite to that where the admission of the explosive mixture takes place, is arranged a rotary valve m provided with openings m^1 , which, when successively brought opposite an exhaust hole m^2 in the cylinder a a^1 a^2 or a^3 , permits the escape of the exhaust gases. This valve m is conical and controlled by a cam n mounted on an axis n^1 receiving a rotary motion from the motor by means of a shaft n^2 and of suitably arranged pinions n^3 . The same cam n controls the two rotary valves of the same group of cylinders, through the medium of disks n^4 mounted on each of the rods m^3 of the valves m ; said disks are provided with semi-spherical projections m^4 engaged in slots in the cam. Each of the disks n^4 is arranged between two springs o and can move on the rod m^3 of the valve m , so as to allow the latter to move slightly inside the cylinder if, by reason of the heat produced by the explosions, it should expand. The rotary valve thus arranged can constitute a make-and-break intended to produce the electric spark determining the ignition of the explosive mixture. To that effect each valve m is internally provided with projections p , one of which is always brought in contact with the terminal q of an igniter before the explosive mixture is compressed by the piston. When this compression is complete, the valve m is moved along by the cam n and the projection p suddenly moves away from the plug q producing a rupture which causes a spark igniting the mixture.

The operation of the motor thus arranged is as follows taking, as example, the two cylinders a and a^1 forming one of the groups

and referring to Figs. 7 to 14 of the drawings: Supposing the pistons are at the end of their stroke, the cylinder a at the compression cycle and the cylinder a^1 at the exhaust, cycle, as shown in Fig. 7, if these pistons move forward as illustrated Fig. 8 their rods move along the valves i which latter open. The air and the combustible liquid are admitted in the two cylinders and the mixture can pass from one cylinder to the other through the conduit-pipe b . When the pistons c and c^1 come to the end of their stroke, the compressed mixture contained in the cylinder a is ignited and the valve m of the cylinder a^1 , which was at the exhaust cycle, rotates, closing the opening m^2 of said cylinder (Fig. 9). Under the action of the explosion of the explosive mixture, the pistons c and c^1 move backward, as shown in Fig. 10, and the valves i are closed. The gases thus produced press the valve h of the piston c on to its seat and this piston itself is pressed on to the disk f . The piston c pushes back the explosive mixture previously admitted. These fresh gases, passing through the conduit-pipe b , are sent into the cylinder a^1 and, acting upon the inner face of the piston c^1 , drive the latter forward the distance it moves on its rod. The gases passing around the disk f and through the opening g push the valve h which opens, as illustrated in Fig. 6. The fresh gases thus pass therefore in front of the piston c^1 into the cylinder a^1 until the pistons c and c^1 have arrived to the end of their stroke. At this moment, the pistons are brought back to the front and the valves i open. The cylinder a comes to the exhaust cycle while fresh gas, contained in the cylinder a^1 , is compressed, as shown in Fig. 11 and presses the valve h against the piston c^1 and the latter against the disk f . During this time, a new charge of fresh gas is admitted into the two cylinders a and a^1 . When the two pistons c and c^1 come to the end of their stroke, the compressed mixture is ignited in the cylinder a^1 (Fig. 12). The pistons c and c^1 are then driven backward, the inlet valve h of the piston c^1 is closed and the fresh gases previously admitted are driven backward through the conduit-pipe b into the cylinder a . These gases displace the piston c and its valve h and pass in front of the said piston, as indicated in Fig. 13. When they are at the end of their stroke, the pistons c and c^1 return to the front, the explosive mixture is compressed in the cylinder a and the exhaust gases escape from the cylinder a^1 , as shown in Fig. 14 and the same cycle as that just described is repeated. It is of course understood that the cycle is reproduced also in the cylinders a^2 and a^3 . On the return backward of the pistons c and c^1 , in order to prevent the latter from compressing at the end of their stroke a certain quantity of gas

in the housings *j*, which would have for effect to prevent the immediate opening of the valves *i*, the piston rods *d* *d*¹ *d*² and *d*³ are each provided with two holes *r* and *r*¹.
 5 These holes open into the hollow part of the rod and they are so arranged that, when the piston is at the end of its stroke, the hole *r* is brought outside the cylinder and consequently opens at the exterior. In these conditions the gases which might be compressed in the housings, pass through the hole *r*¹, the hollow part of the rod *d*, the hole *r* and escape in the atmosphere. When the piston moves again forward, the valve, not being subjected to any pressure, immediately opens in order to permit the admission of the liquid fuel and the air.
 10

The different inner parts of each group of cylinders are lubricated by means of a 20 lubricating device of the following construction.

Between the two groups of cylinders *a* *a*¹ and *a*² *a*³ and above these cylinders is arranged a tank or vessel *s* receiving the lubricating oil. This tank communicates by 25 means of two curved pipes *s*¹ and *s*², with the upper part of the cylinders *a* and *a*². A ball-valve *s*³ is suitably arranged in the middle of these pipes (Fig. 1). On the 30 other hand, at the lower part of the cylinders *a*¹ and *a*³ open two pipes *t* and *t*¹ the other end of which, provided with a ball-valve *t*², engages in an auxiliary box *u* or *u*¹ hermetically closed by a stopper. Another 35 pipe *v* leads from this auxiliary box *t* or *t*¹ to a multiple way-cock *v*¹ on which are branched two pipes *w* *w*¹ connecting this cock with the tank *s*. The cock *v* carries a handle *v*² which is controlled by two tappets 40 *x* and *x*¹ respectively secured on the piston rods *d*¹ and *d*³.

By examining the group of cylinders *a* *a*¹ (Fig. 1) it will be seen that, when the pistons move forward, the oil contained in the 45 tank *s* is sucked in, the valve *s*³ is lifted and the oil enters in the cylinder *a* and in the cylinder *a*¹, by passing through the conduit-pipe *b*. When the pistons again move backward, this oil is pushed back with a certain 50 quantity of gas in the auxiliary box *u*, then, passing through the pipe *v*, the cock *v*¹ which at this time is open, and the pipe *w*, enters the tank *s*, where the gas which was driven along exerts a pressure on the oil contained 55 therein. Upon a new stroke of the pistons, the valve *s*³ opens, while the valve *t*² closes and the oil is again brought along under pressure through the pipe *s*¹. At each displacement of the piston rods, the cock is 60 opened by means of the handle *v*² and of the tappets *x* and *x*¹, so as to permit to put the auxiliary boxes *u* and *u*¹ into communication with the pipes *w* and *w*¹ and, consequently, with the tank *s*. In order to avoid this tank 65 being subjected to a too high pressure of

the gases which are pushed back therein, a valve *y* opens automatically when a determined pressure is reached.

In the example illustrated Figs. 1 to 6, the motor comprises two groups of two cylinders, but it is to be understood that this number could be increased at will, by suitably bending the shaft *e*¹. The motor could also comprise only two vertically arranged cylinders, as shown in Fig. 15 of the drawings. 70 75

The present system of motor develops a great horse power under a small volume, by reason of the mode of admission of the explosive mixture by the part of the cylinders 80 opposite to that where the ignition is produced, as this mixture being admitted at a relatively low temperature, a greater quantity of fresh gas can enter the cylinder. Moreover, the explosive mixture being 85 driven away from the two cylinders to the front of the piston of one of these cylinders, this mixture is subjected to a first compression and is afterward compressed a second time by the return to the front of the 90 same piston, previously to the ignition. A much more considerable volume of compressed explosive gas can thus be obtained than with the simple suction and compression systems, ordinarily used in explosive 95 motors. On the other hand, the pressure lubricating device permits to obtain a perfect lubrication of the inner parts of the motor.

The above arrangements are only given 100 by way of example, the forms, dimensions and details may vary without modifying the principle of the invention.

Claims:

1. In an explosion motor, a pair of superimposed cylinders communicating with each other at one end, inlets for the liquid fuel and air at the same end of the cylinders, an ignition device at the ends of the cylinders opposite that which the air and fuel inlets 110 are arranged, and a valved piston in each of the said cylinders.

2. In an explosion motor, hollow pistons in the cylinders and movable on the ends of their rods, the pistons having central openings, disks secured on the ends of the piston rods within the pistons, each disk being of a diameter less than the internal diameter of the piston, abutments secured to the inner faces of the pistons, and a valve for controlling the opening of each piston, said valves operating with the pistons to admit the explosive mixture in front of said piston. 115 120

3. In an explosion motor, groups of cylinders, each cylinder having a housing at one end, a piston in each cylinder, valves permitting the admission of liquid fuel and air to the cylinders, each of these valves being frictionally mounted upon one of the piston 125 130

- rods and located in a housing limiting its displacement, the two valves of each group of cylinders serving for the admission of the air, while only one serves to admit the liquid fuel.
4. In an explosion motor, a cylinder, and a piston in the cylinder and having its piston rod hollow for a part of its length and provided with two lateral holes for putting the cylinder into communication with the atmosphere at the end of the stroke of the piston.
5. In an explosion motor, a cylinder, a valved piston in the cylinder, a fuel inlet at one end of the cylinder around the piston rod, a housing within the cylinder at the said inlet, a valve loosely mounted on the piston rod within the housing and controlling said inlet, and an igniting device at the end of the cylinder opposite that having the fuel inlet.
6. In an explosion motor, a cylinder, a valved piston in the cylinder, means for admitting fuel at one end of the cylinder, an igniting device at the opposite end of the cylinder, and an exhaust valve at the end of the cylinder having the igniting device and controlling the said igniting device.
7. In an explosion motor, a cylinder, a piston in the cylinder and having a piston rod upon the ends of which it has limited sliding movement, said piston having an opening therein and provided with means for permitting the passage of the explosive mixture in front of it, a valve slidably connected with the piston rod and controlling the opening of the piston, means for admitting fuel at one end of the cylinder, and an igniting device at the opposite end of the cylinder.
8. In an explosion motor, a cylinder, a piston rod having a bore in one end and provided with a flange adjacent to said end, a cup shaped piston having limited sliding movement on the piston rod and provided with an opening in its bottom into which the end of the piston rod is adapted to enter, a valve adapted to engage the outer face of the bottom of the cup-shaped piston and having a stem extending into and slidably held in the bore of the piston rod, means for admitting fuel at one end of the cylinder, and an igniting device at the opposite end of the cylinder.
9. In an explosion motor, a cylinder, a valved piston in the cylinder, means for admitting fuel at one end of the cylinder,
- an igniting device at the other end of the cylinder, and a rotary exhaust valve at the end of the cylinder having the igniting device and carrying a member of the said igniting device.
10. In an explosion motor, a cylinder having a housing at one end, a piston rod extending into the cylinder through the housing, said piston rod being hollow for a portion of its length and provided with lateral openings, the opening in the cylinder through which the piston rod extends forming a fuel inlet, a valve mounted loosely on the piston rod in the said housing, a valved piston on the piston rod, and an igniting device at the end of the cylinder opposite that having the housing.
11. In an explosion motor, a cylinder, a piston having limited sliding movement on the end of the piston rod and having an opening therein, said piston being provided with means for permitting the passage of the explosive mixture in front of it, and a valve at the outer face of the piston for closing the opening thereof, said valve having a stem slidably connected with the piston rod.
12. In an explosion motor, a cylinder, a piston rod having a bore in one end, a piston having limited sliding movement on the piston rod and provided with an opening into which the end of the piston rod is adapted to enter, and a valve for closing the opening of the piston and having its stem slidably held in the bore of the piston rod.
13. In an explosion motor, a cylinder, a piston rod having a bore in one end and provided with spaced openings leading into the bore, a piston having limited sliding movement on the piston rod and provided with an opening into which the end of the piston rod is adapted to enter, and a valve at the outer face of the piston and having its stem slidably held in the bore of the piston rod, said valve being adapted to close the opening of the piston at the time the piston rod is in the opening of the piston.
- The foregoing specification of my "explosion motor" signed by me this second day of September, 1910.
